UNITED STATES PATENT OFFICE

ALVIN L. JOHNSON, OF WORCESTER, MASSACHUSETTS, ASSIGNOR TO W. GOULDING
WARREN, OF HOLDEN, MASSACHUSETTS

LIFTING JACK

Application filed November 25, 1927. Serial No. 235,583.

This invention relates to a lifting jack of the type in which a single lifting element is employed.

The principal object of the invention is to provide a construction in which the single lifting element, as for example, a screw or rack, can be raised to such a height that it projects above the top of the base or casing a distance greater than the height of said base or casing, and at the same time avoids the danger of dislodgement of the load by the turning of the screw. The invention also involves the construction of the lifting element in two or more parts, preferably three, the upper part being substantially solid and the lower parts being arranged to be located under it to support it, at certain times. I provide means whereby, when the lifting element descends into the casing far enough, the lower parts of the lifting element will automatically move laterally to allow the upper part to move down along the side of them and preferably between them and also, of course, to provide means whereby, when the upper element is lifted up to a certain point, the lower parts will automatically come together without attention. Here they not only support the upper part but constitute a continuation thereof adapted to be operated upon by the operating means in a continuous manner without any interruption. In this way the upper part of the lifting element can be made almost as long as the height of the casing and this entire part of the jack can be lifted above the top of the jack casing by a distance equal to the height of the lower part of the element minus so much of the same as may be needed to hold it in the casing and in operating contact with the operating means.

Other objects and advantages of the invention will appear hereinafter.

Reference is to be had to the accompanying drawings in which

Fig. 1 is a side view of a screw jack constructed in accordance with this invention and shown with the lifting elements raised;

Fig. 2 is a diametrical sectional view showing the parts in the position they assume when the change is about to take place on the

ascending motion or the position just after the change has taken place on the descending motion;

Fig. 3 is a view showing the upper part of the lifting element in section and its attached member at the bottom in elevation;

Fig. 4 is a view similar to Fig. 3 with the central section taken along a vertical plane at right angles thereto;

Fig. 5 is a sectional view on the line 5—5 of Fig. 2;

Fig. 6 is a sectional view on the same line showing the parts in an entirely retracted position;

Fig. 7 is a sectional view of part of the device on the same plane as Fig. 2, showing the lower parts of the lifting element contracted together.

Fig. 8 is a sectional view taken on a vertical plane of a rack jack showing the same principle applied thereto;

Fig. 9 is a sectional view of the same taken on the line 9—9 of Fig. 8 and showing the upper rack section partly lowered into the casing;

Fig. 10 is an edge view of the rack showing the lower part and the rod below in section;

Fig. 11 is a front view showing the racks in raised position;

Fig. 12 is a sectional view of part of the device on the same plane as Fig. 9 showing the lifting of the lower parts of the rack;

Fig. 13 is a sectional view on the line 13—13 of Fig. 9, and

Fig. 14 is a similar sectional view with the parts in the position they assume when the upper part of the rack is raised a little higher.

In the first seven figures, I have shown the invention as applied to a screw jack comprising a base or casing 10, which is hollow and is shown as provided with a hollow frame 8 above the top 9. In this frame is a nut 11 having a gear operated by a pinion 12 and shaft 13. This constitutes the operating means. The frame 8 has two openings 29 and 29^a in its top and bottom constituting a guide for the screw as usual. The nut 11 is shown as supported by ball bearings 14 on 100

the top 9 of the casing 10. This casing is provided interiorly with two pairs of conical or slanting surfaces 15 and 16 for a purpose to be described.

5 The lifting element consists of an upper part shown here in the form of a screw 20 and having a rest 21 for the work and two lower parts 22, each one being shown in the form of an arcuate member, in this case, 10 semicircular in cross section. These two 15 parts have a screw thread constituting a continuation of the thread on the part 20. When these two parts 22 are brought together in the position shown in Figs. 1 and 7 they are continuous with the upper part of the lifting member 20 and, in the form shown, constitute a continuous screw. In other words, there is an area extending from top to bottom of this continuous screw which is provided with screw threads cooperating with the nut 11 to lift the member 20, not only when that member is in engagement with the screw threads of the nut, but also when the two members 22 are in engagement with it.

20 25 The upper part 20, which I call the solid part because it is in one piece, is provided with a passage up through it and a rod 23 is adapted to be located in this passage. The part 20 is provided with a pair of guide pins 24 projecting radially into the interior and 30 adapted to engage in longitudinal slots 25 which are cut into the rod 23. These slots extend nearly to the top of the rod and, as shown in Figs. 3 and 4, the rod hangs from 35 the pins 24 when the screw 20 is raised enough to lift the bottom of the rod off the bottom of the casing. This is a telescoping construction allowing the screw 20 to descend to the bottom of the casing when the 40 screw jack is contracted. The rod 23 has a base 26 adapted to rest on the base of the casing which keeps the screw members from rotating at all times. In the slot or slots 25 are a pair of opposite springs 27. These 45 springs are fastened at the top in the slots by means of pins 28 or other means and free to slide in the slots at the bottom. These 50 two springs are adapted to engage the interior concave surfaces of the two lower parts 22 and force them out into the position 55 shown in Fig. 2 when these lower parts descend from the passage 29 down through the top 8 of the casing.

The members 22 are provided with projections 28 having slanting upper surfaces adapted to engage the conical or slanting surfaces 16 when the two parts 22 are forced apart. This constitutes means for forcing them together at the bottom whenever they 60 are raised. It will be noted that the bottoms of these members 22 rest on the plate 26 and when that is raised by the raising of the screw 20, these two parts are forced to move upwardly and they are also forced to move inwardly at the bottom on account of these 65

conical surfaces. They are also forced to move inwardly at the top on account of engagement with the slanting surfaces 15.

In the operation of the device, assuming the lifting member to be contracted with the screw 20 clear down to the bottom, it will still engage in the nut 11. The shaft 13 being turned, the nut rotates and raises the screw 20 in the usual way with single screw jacks, without turning. When the screw has reached the point shown in Figs. 2, 3 and 4 the continuation of the turning of the nut 11 causes the screw 20 to move up still further. The plate 26 at this time is positively moved upward with it and raises the two side parts 22. These are forced together against the opposition of the springs 27 by the conical surfaces 15 and 16 until the two parts 22 come into contact with each other at the center when they constitute a second screw in continuation of the screw 20. This screw follows the screw 20 into the nut 11 and is raised in the same manner as the screw 20 without any interruption or change in rotation of the nut.

90 On the downward motion the parts 22 are moved outwardly by the springs 27 as soon as they get out of the passage 29. This outward motion is controlled by the conical surfaces 15 and also controlled at the bottom by the conical surfaces 16. The parts are so proportioned that they will move outwardly far enough to permit the screw 20 to descend between them, which is shown in Fig. 6. As this screw descends it forces inwardly the two springs 27 but that has no effect on the operation as there is nothing now to move the two parts 22. The screw 20 therefore can be lowered until its bottom rests against the plate 26.

105 In either way it will be seen that a jack is furnished in which the entire length of the upper part 20 can be lifted materially above the top of the jack and the entire height of the jack, when expanded, is nearly three times what it is when contracted. Yet the screws do not turn at any time and there is no danger of working the load off the support 21 by any turning or other motion of the screws. The construction is simple and the operation 110 entirely automatic. The changes in position take place without jar or binding and the lifting of the load does not become harder due to any binding of the screws, as with one screw inside another, when it is lifted to nearly the maximum height but it is practically always the same. The parts are simple and can be made by economic shop methods.

115 In the form shown on the second sheet the principles are substantially the same as applied to a rack jack. Here the casing 30 is provided with pawls 31 operated by a lever 33 and controlled by a cam lever 32 as is usual in rack jacks. The casing is provided with a 120 guide 39 at the top for guiding the racks. 125

- The casing 30 is provided with two pairs of slanting surfaces 35 and 36 having the same purposes as the conical surfaces 15 and 16 in the other form.
- 5 The upper part of the lifting element is shown in the form of a rack 40 having teeth along one side and provided with a support 41 for the load. The lower part of the lifting element consists of two racks 42 having a similar set of teeth. A rod 43 is connected with the part 40 of the rack by pins 44 and is provided with grooves 45 along its sides and with a lifting plate 46 fixed to its lower end. In these grooves is a double spring 47 which is shown here as in one piece and operating in all respects like the springs 27. The two rack members 42 are provided with projections 48 slanting on top and extending in opposite directions.
- 10 The operation of this jack will be understood from the description of the operation of the screw jack given above. It is operated by the lever 33 in the same manner as any rack jack. The descent of the rack from the position shown in Fig. 8 to the position shown in Fig. 9 allows the springs 47 to force the racks 42 apart far enough to allow the rack 40 to descend between them. The racks 42 cannot separate fully until the projections 15 48 come down low enough to enter under the slanting surfaces 36 and they rest on the plate 46. As the rack 40 descends it compresses the springs 47 as in the other case.
- Upon rising, the opposite action takes place and the positive force of lifting of the racks 42 by the plate 46, as the rack 40 rises, causes the slanting surfaces 35 and 36 to contract the racks 42 in opposition to the springs 47. Thus they come together under the rack 40 and in due season are operated upon by the pawls 31 to force the double length rack up as shown in Fig. 8.
- The rack is continuous from top to bottom and the rod 43, on account of its connection with the rack 40 and its support of the racks 42, prevents the swinging of the rack 40 and insures a rigid construction for supporting the load.
- Although I have illustrated and described only two forms of the invention I am aware of the fact that other modifications can be made therein by any person skilled in the art without departing from the scope of the invention as expressed in the claims. Therefore, I do not wish to be limited to the details herein disclosed, but what I do claim is:—
1. In a lifting jack, the combination with a casing and an operating mechanism carried thereby, of a lifting member comprising a plurality of parts all adapted to be received in the casing with their lower ends at substantially the same level side by side and in upright position when retracted, and arranged and adapted to be moved directly upwardly through the top of the casing by said operating mechanism one on top of another in vertical alignment.
2. In a lifting jack, the combination with a casing and an operating mechanism carried thereby, of a lifting member comprising a plurality of parts all adapted to be arranged vertically side by side within the casing, one of them being then in operative engagement with the operating mechanism, and means whereby, when said part is moved upwardly to project above the casing, the lower part will move automatically to a position under it and come into operative engagement with said operating mechanism.
3. In a lifting jack, the combination with a casing and an operating mechanism carried thereby, of a lifting member comprising a plurality of parts all adapted to be arranged side by side within the casing, one of them being then in operative engagement with the operating mechanism, and means whereby, when said part is moved upwardly the lower part will move automatically to a position under it and come into operative engagement with said operating mechanism.
4. In a lifting jack, the combination with a base and an operating means, of a lifting member comprising two parts having a continuous area to cooperate with the operating means for raising or lowering said lifting member, and one of said parts comprising two parts normally located side by side in the base, and means for moving the said two parts laterally when the upper part has risen to its top, to bring said areas into registration with each other and permit the operating means to act on the lower part of the lifting member.
5. A lifting jack comprising a lifting member consisting of three parts, two of said parts being laterally separable to provide a space between them for receiving the other part when it is lowered, the ends of the separable parts when they are in contact being located under said other part when it is raised above the separable parts.
6. A lifting jack comprising a lifting member consisting of three parts, two of said parts being laterally separable to provide a space between them for receiving the other part which is adapted to be supported on the ends of the two separable parts when they are in contact with each other, the two parts combined having the same cross section as the other part, and being provided with means by which they can be raised, the other parts also having similar means continuous therewith.
7. In a lifting jack, the combination with a hollow base, of a solid lifting member, and a lifting member consisting of a plurality of parts, means whereby, when the first lifting member is raised in the base, the parts of the second lifting member will be caused to

come together under the first named member to support and lift it, and means whereby, when the two lifting members are lowered to a position in which the second lifting member is located entirely in the base, the parts thereof will remain in vertical position and will separate to allow the first lifting member to be lowered between them.

8. In a lifting jack, the combination with a casing and a rotatable nut carried thereby, of a screw having an upper part in one piece and a lower part, continuous therewith, but in a plurality of movable pieces, and means whereby, upon lowering the screw until its lower end projects below the nut into the casing, the lower pieces will move sideways automatically to allow the upper screw parts to descend into the casing at their sides.

9. In a lifting jack, the combination with a casing and a rotatable nut carried thereby, of a screw having an upper part in one piece and a lower part, continuous therewith, but in a plurality of movable pieces, and means whereby, upon raising the screw, the lower pieces will move sideways automatically to a position under the upper screw part to support the upper part and engage the nut to force the upper part above the top of the casing.

10. In a lifting jack, the combination with a casing and an operating nut, of a screw threaded lifting member comprising an upper part having a screw thread adapted to cooperate with the nut to lift the member without turning it, said lifting member also comprising a plurality of separate lower parts which, when brought together, form a screw continuous with the screw of the upper part, also adapted to cooperate with said nut for the same purpose, and a rod slideable in the upper part and connected with it to move upwardly with it and having means whereby said lower screw parts will rise with the rod, and a pair of springs carried by the rod and normally pressing against the lower screw parts, the casing having a pair of slanting surfaces at the bottom and a pair of slanting surfaces at the top for engaging said lower parts and forcing them inwardly against the spring, about the rod, and under the upper screw part when the lower screw parts are lifted to a position to start to project through said opening.

11. In a lifting jack, the combination with a casing having an opening at the top, and an operating nut, of a screw threaded lifting member comprising an upper part having a continuous screw thread adapted to cooperate with the nut to lift the member without turning it, said lifting member also comprising a plurality of separate lower parts which, when brought together, form a screw continuous with the screw of the upper part, also adapted to cooperate with said nut for the same purpose, and a rod slideable in the upper part and connected with it to move upwardly with it and having means whereby said lower screw parts will rise with the rod.

12. In a lifting jack, the combination with a casing having an opening at the top, and an operating nut, of a screw threaded lifting member comprising an upper part having a screw thread adapted to cooperate with the nut to lift the member without turning it, said lifting member also comprising a plurality of separate parts which, when brought together, form a screw continuous with the screw of the upper part, a rod in the upper part and connected with it, and yielding means carried by said rod and engaging the inner sides of the lower screw parts for forcing them out away from each other whenever they are free to move, the casing having means cooperating with the lower screw parts for forcing them together about the rod under the upper part when lifted to the top of the casing.

13. In a lifting jack, the combination with a casing having an opening at the top, and an operating nut, of a screw threaded lifting member comprising an upper part having a screw thread and a plurality of separate parts which, when brought together, form a screw continuous with the screw of the upper part, a rod in the upper part and connected with it, and yielding means carried by said rod and engaging the inner sides of the lower screw parts for forcing them out away from each other whenever they are free to move, the casing having means cooperating with the lower screw parts for forcing them together about the rod under the upper part when lifted to the top of the casing.

14. A lifting rack for a jack comprising an upper member and two lower members independently movable sideways, and a rod slideable in the upper member and depending from the bottom thereof having means for supporting the side members at such a level that their tops are just under the bottom of the upper member, whereby the three members together constitute a continuous rack.

15. A lifting member for a jack comprising a screw in three parts, one part being cylindrical and the other two parts arcuate in transverse cross section, said two parts being separable radially to have a space between them sufficient to receive the first mentioned part.

16. In a lifting jack, the combination with a casing and an operating means carried thereby, of a lifting member comprising an

17. A lifting member for a jack comprising a screw in three parts, one part being cylindrical and the other two parts arcuate in transverse cross section, said two parts being separable radially to have a space between them sufficient to receive the first mentioned part.

18. In a lifting jack, the combination with a casing and an operating means carried thereby, of a lifting member comprising an

19. A lifting member for a jack comprising a screw in three parts, one part being cylindrical and the other two parts arcuate in transverse cross section, said two parts being separable radially to have a space between them sufficient to receive the first mentioned part.

20. In a lifting jack, the combination with a casing and an operating means carried thereby, of a lifting member comprising an

- upper part, a rod telescoping therein, and a lower part supported by the rod and movable sideways to permit the upper part to descend into the casing past the lower part,
 5 said rod hanging from said upper part when raised to stabilize the lifting member in the casing.
17. A jack comprising, in combination, a standard, a screw, with upper section and lower split section, all operable into and out of said standard, and means for spreading in half the said split lower section of the screw to permit said upper section to pass within it.
18. A jack comprising, in combination, a standard, a sectional screw keyed to said standard and slidable therein, and means within said screw for spreading one of said sections to permit another section to slide within it.
19. A jack comprising, in combination, a standard, a sectional screw with lower portion adapted to be spread open to permit the upper portion to pass within it, means within the screw for spreading said lower portion when within the standard, and means within the standard adapted to close said split portion of screw as the screw travels out of said standard.
20. A jack comprising, in combination, a standard, a sectional screw keyed to said standard and slidable therein, a spring arranged to spread one section of the screw within the standard to permit passage within it of another section of the screw, and means within said standard and operable during outward travel of the screw for closing said spread screw section.
21. A jack comprising, in combination, a standard, a sectional screw with lower portion adapted to be spread open to permit the upper portion to pass within it, spring arms tending to spread said lower portion and inclined surfaces at upper and lower ends of said standard adapted to permit said spreading when said lower portion is wholly within said standard, and adapted to close said lower section as it moves upward out of said standard.
- 50 In testimony whereof I have hereunto affixed my signature.

ALVIN L. JOHNSON.
